ATTORNEY

UNITED STATES PATENT OFFICE.

FRANK MEDEIROS MENDONCA, OF HILO, TERRITORY OF HAWAII.

LAMP-BURNER.

1,235,224.

Specification of Letters Patent. Patented July 31, 1917.

Application filed February 16, 1917. Serial No. 149,099.

To all whom it may concern:

Be it known that I, FRANK M. MENDONCA, a citizen of the United States, residing at Hilo, Territory of Hawaii, have invented 5 new and useful Improvements in Lamp-Burners, of which the following is a specification.

This invention relates to lamp burners for kerosene lamps, and it has for its object to 10 provide a lamp burner with a simple and improved extinguishing device whereby the flame may be extinguished without resorting to blowing down the chimney, an expedient which has frequently resulted in 15 igniting the oil contained in the reservoir of the lamp, thereby causing disastrous accidents.

A further object of the invention is to 20 provide a lamp burner having a swingingly supported extinguishing member and means whereby the same may be conveniently actuated.

A further object of the invention is to 25 provide a device of the class described of simple and improved construction, wherein a stop member is provided to limit the movement of the swingingly supported extinguishing member.

With these and other ends in view which 30 will readily appear as the nature of the invention is better understood, the same consists in the improved construction and novel arrangement and combination of parts which will be hereinafter fully described 35 and particularly pointed out in the claims.

In the accompanying drawing has been 40 illustrated a simple and preferred form of the invention, it being, however, understood that no limitation is necessarily made to the precise structural details therein exhibited, but that changes, alterations and modifications within the scope of the claims may be resorted to when desired.

In the drawing, 45 Figure 1 is a front view of a burner constructed in accordance with the invention, the cap of the burner having been partly broken away.

Fig. 2 is a horizontal sectional view taken 50 through the cap and looking down upon the extinguishing device.

Fig. 3 is a vertical sectional view taken on the line 3—3 in Fig. 2.

Fig. 4 is a vertical sectional view taken 55 substantially at right angles to Fig. 3.

Corresponding parts in the several fig-

ures of the drawing are denoted by like characters of reference.

The lamp burner A which is of ordinary conventional construction embodies a neck 60 15 having a threaded portion 16, the perforated diaphragm 17 having upwardly extending chimney holders 18, the cap 19 which is hingedly connected with the diaphragm, and the wick raising stem 19 having a button or handle 20 whereby it may be rotated.

The side walls of the wick tube C are provided with externally disposed pivots 21 affording supports for the extinguishing 70 member B which is composed of approximately semi-circular side walls 22, 23 which are spaced apart and connected together at one end by an end wall 24, said end wall and side walls being preferably formed of 75 a single piece of sheet metal which, after being cut to the proper form, may be readily bent to produce the device. The side walls 22, 23 are each provided with an aperture 25 engaging one of the pivot members 21, and the side wall 22 is provided with a pinion 26 secured on the external face thereof in concentric relation with the aperture 25. Secured on the diaphragm 17 adjacent to one end of the wick tube 80 85 C is a stop member 27 which lies in the path of the end wall 24 of the extinguishing member. The latter is so arranged and proportioned that in one position thereof the straight edges of the approximately 90 semi-circular side walls will coincide with the top edge of the wick tube, being disposed approximately in the horizontal plane of said top edge while in another position of the extinguishing member the curved 95 edges of the side walls 22, 23 will extend materially above the top of the wick tube. It is in this last named position that the end wall 24 engages the stop member 27.

For the purpose of operating the extinguishing member there is provided a stem or shaft 28, suitably supported for rotation approximately at right angles to the wick raising stem 19, and having a button or handle 29 whereby it may be rotated. 100 The stem 28 carries a segment rack 30 which meshes with the pinion 26. It follows that by rotation about its axis of the stem 28 the pinion 26 will be rotated, thereby swinging the extinguishing member about the axis 105 110 of the pivot members 21.

The operation of this device will be read-

ily understood. When the straight edges of the side walls of the extinguishing member are juxtaposed to the top of the wick tube, the lamp may be conveniently lighted and will burn unobstructedly. To extinguish the flame it is only necessary to rotate the stem 28, thereby swinging the extinguishing member about the axis of the pivot members 21, thereby carrying the curved edges 10 of the side walls 22, 23 above the flame which will thus be quickly smothered without the least danger of fire being projected downwardly through the wick tube and igniting the gases contained in the lamp reservoir.

Having thus described the invention, what is claimed as new is:

1. A lamp burner having a wick tube provided with pivot members on the side walls thereof, an extinguishing member swingingly supported on the pivot members, said extinguishing member comprising ap-

proximately semi-circular side walls and an end wall whereby said side walls are connected and spaced apart, means for actuating the extinguishing member, and a stop element supported on the diaphragm of the lamp burner in the path of the end wall of the extinguishing member. 25

2. A lamp burner having a wick tube the side walls of which are provided with pivot members, an extinguishing member swingingly supported on the pivot members, said extinguishing member comprising side walls and an end wall whereby said side walls are connected and spaced apart, a pinion fixed externally on one of the side walls in concentric relation to the axis of the pivot members, a stem supported for rotation and having an actuating handle, and a segment 40 rack carried by said stem and engaging the pinion.

In testimony whereof I affix my signature.

FRANK MEDEIROS MENDONCA.
